US00D896731S

(12) **United States Design Patent** (10) Patent No.: **US D896,731 S**
(45) Date of Patent: **** Sep. 22, 2020**

(54) **AERIAL VEHICLE**

(71) Applicant: **SZ DJI Technology Co., Ltd.**,
Shenzhen (CN)

(72) Inventors: **Bo Liang**, Shenzhen (CN); **Li Qiu**,
Shenzhen (CN)

(73) Assignee: **SZ DJI Technology Co., Ltd.**,
Shenzhen (CN)

(**) Term: **15 Years**

(21) Appl. No.: **29/701,938**

(22) Filed: **Aug. 15, 2019**

Related U.S. Application Data

(63) Continuation of application No. 29/642,455, filed on Mar. 29, 2018, now Pat. No. Des. 862,360, which is a continuation of application No. 29/595,105, filed on Feb. 24, 2017, now Pat. No. Des. 816,582.

(51) **LOC (12) Cl.** **12-02**

(52) **U.S. Cl.**

USPC **D12/328**

(57) **CLAIM**

The ornamental design for an aerial vehicle, as shown and described.

DESCRIPTION

FIG. 1 is a top front perspective view of an aerial vehicle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the aerial vehicle that form no part of the claimed design.

1 Claim, 8 Drawing Sheets
